UNITED STATES PATENT OFFICE.

JAMES M. THORNTON, OF HARRISBURG, PENNSYLVANIA.

UNION UNDERGARMENT.

1,198,488.

Specification of Letters Patent. Patented Sept. 19, 1916.

Application filed December 7, 1915. Serial No. 65,455.

To all whom it may concern:

Be it known that I, JAMES M. THORNTON, a citizen of the United States, residing at Harrisburg, county of Dauphin, and State 5 of Pennsylvania, have invented a new and useful Improvement in Union Undergarments, of which the following is a full, clear, and exact description, reference being had to the accompanying drawings, which form 10 a part of this specification.

The object of my invention is to provide a union suit, more particularly adapted for women's underwear, in which provision is made for a great degree of elasticity in the 15 hip portion and which possesses other advantages which will be apparent from the following description of the accompanying illustration of a preferred embodiment of my invention in which—

20 Figure 1 is a front view of the garment. Fig. 2 is a rear view of the garment. Fig. 3 is a diagram of the waist or body portion before attachment to the leg portion. Figs. 25 4 and 5 are diagrams of the respective leg portions.

The garment is made, as heretofore, of three parts, sewed together in the region of the hips and waist, namely, a bust or waist portion *a* and two tubular leg portions *b* and 30 *c*. In my invention, the lower edge *d* of the waist extends straight across in the front, while at the rear the edge is of angular form, the same extending upwardly from the sides to the center, thereby forming an 35 angle whose apex is at the top and whose sides *e* and *f* open downwardly.

Each leg portion consists of a tube the upper edge of which is sewed to the waist along its straight horizontal front edge *d* 40 from the side to a little beyond its center, and along its inclined front edge *e* or *f* from the same side to the apex of the angle and also to the body of the waist along a horizontal line *g* or *h* extending from said 45 angle apex toward, but terminating short of, the opposite side of the garment. Each tube is cut away at its inner side downwardly from the end of its rear edge and from

the end of the front edge to a point *i* a substantial distance below the latter. Thus one 50 leg portion overlaps the other, slightly at the front and very considerably at the back, in such manner as to afford a secure closure which may, however, readily be opened.

It will be noted that the waist along its 55 opposite sides extends over the hip portion of the garment and that it is free of any seam or attachment to the leg portion which would tend to decrease its natural elasticity. In other words, at the front of the garment, 60 the seam *d* between the waist and the tubular legs and which extends straight across the garment is below the hip portion, while at the rear the straight horizontal seam *g* *h* 65 uniting the upper edge of the tubular legs to the waist extends only across the central portion of the rear of the garment. Thus opposite sides of the garment in the region of the hips are free to expand to the limit of elasticity of the material of which the 70 garment is made.

Having now fully described my invention, what I claim and desire to protect by Letters Patent is:

A union undergarment comprising a waist 75 having at the front a straight horizontal lower edge at a relatively low level between opposite sides of the garment and an angular rear edge extending upwardly from opposite sides of the garment toward the center thereof with the apex of the angle at a relatively high level, and two overlapping tubular leg portions each of which is sewed at the front from one side of the garment along a part of the lower edge of the waist 80 and at the rear from the same side of the garment along one inclined edge of the waist and thence along the body of the waist toward, but terminating substantially short 85 of, the opposite side of the garment. 90

In testimony of which invention, I have hereunto set my hand, at Harrisburg, Pa., on this 3rd day of December, 1915.

JAMES M. THORNTON.

Witness:

LEO E. CARROLL.
